(57) **CLAIM**

The ornamental design for a wheel, as shown and described.

DESCRIPTION

FIG. 1 is a front, top, right perspective view for a wheel, showing the new design;

FIG. 2 is a front, bottom, left perspective view thereof;

FIG. 3 is a front elevation view thereof;

FIG. 4 is a rear elevation view thereof;

FIG. 5 is a left side thereof;

FIG. 6 is a right side view thereof;

FIG. 7 is a top plan view thereof; and,

FIG. 8 is a bottom plan view thereof.

The broken lines of uneven length illustrate the boundary of the claimed design. The broken lines of even length shown in the drawings illustrate portions of the Wheel that form no part of the claimed design.

1 Claim, 8 Drawing Sheets
